CALIBRATION OF AUTOMATIC CIRCUIT BREAKERS

Thomas M. Cole, New York, N. Y., assignor to
Federal Electric Products Company, Newark,
N. J., a corporation of Delaware

Application March 2, 1951, Serial No. 213,591

13 Claims. (Cl. 200—116)

1

This invention relates to an improved method of calibrating automatic circuit breakers and to circuit breakers which are adapted for the practice of said method.

This application is a continuation-in-part of my copending application for circuit breakers Ser. No. 127,433 filed November 15, 1949.

The primary object of the present invention is to provide a simplified and yet micromatically accurate method for calibrating an automatic circuit breaker.

Another object is provision in an automatic circuit breaker of simplified means for adjusting the relative disposition of the actuating means and the bi-metallic element for latch thereof for calibration purposes.

The above and other objects, features and advantages of the present invention will be more fully understood from the following description considered in connection with the accompanying illustrative drawings.

In the drawings:

Fig. 1 is a perspective view of an automatic circuit breaker illustrating the calibrated condition thereof pursuant to the presently preferred mode of practicing the present invention, the cover or one side of the casing being removed and the breaker being closed;

Fig. 2 is a fragmentary view of a sub-assembly of the circuit breaker mechanism in uncalibrated condition;

Fig. 3 is a view similar to Fig. 2 showing the sub-assembly thereof in calibrated condition, pursuant to one method of practicing the invention;

Fig. 4 is a sectional view taken on the line 4—4 of Fig. 3;

Fig. 5 is a composite view similar to Figs. 2 and 3, illustrating the presently preferred embodiment of the invention before the tapered tool is removed; and

Fig. 6 is a sectional view taken on the line 6—6 of Fig. 5.

In general, the circuit breaker illustrated herein and in my above mentioned prior application comprises a movable contact member which carries the movable contact for engagement with and disengagement from the stationary contact of the circuit breaker. Said movable contact member is provided with an actuator which is releasably latched to said movable contact member by means of a current responsive or other overload device which is carried by the movable contact member and releasably engages said actuator under normal load conditions so as to

2

enable the movable contact member to be held in circuit closed position, or to be manually moved to and from said position, and which, upon release of said actuator, results in the movement of said movable contact member automatically to its open circuit position.

Briefly described, the provision for calibrating the circuit breaker, pursuant to the present invention, comprises means to facilitate displacement of a part of the movable contact member of the circuit breaker in relation to another part thereof in such manner as to move the actuator in relation to the current responsive or overload device so as to adjust the releasably engaged portions of the actuator and the current responsive device. In accordance with the presently preferred mode of practicing the present invention, an opening is provided at the edge of said part of the movable contact member and a tapering pin or other tool is pressed into said opening for accomplishing the displacement of said part of the movable contact member. Although it is presently preferred that the tool be removed from said opening, following the calibration operation, it is within the scope of the present invention to allow the tapering pin, used as the calibrating tool, to remain permanently in said opening of the movable contact member.

Referring now to the drawings in detail, there is shown in Fig. 1 an automatic circuit breaker 10 provided with the body part 12 of a two part insulated casing or housing, as in my above mentioned application, the cover thereof being removed for purposes of illustration of the present invention. The circuit breaker mechanism 11 provided in said body part, as here shown, comprises the pivotally mounted movable contact arm 14 provided with the movable contact 16 at one end thereof for engagement with and disengagement from a companion stationary contact 18 provided on a solderless terminal connector 20. At its other end, the movable arm 14 is provided with a pivotally mounted actuator 22 which is in operative engagement with the handle or manual operating member 24 by means of a resilient link 26. The movable contact arm 14 is also provided with a bi-metallic element or latch 28, the free end of which is in latched engagement with the actuator 22 in the circuit-making or closed condition of the mechanism. The latch is connected to a stab element 30, which constitutes the other terminal of the circuit breaker, by means of a flexible conductor 32. As here shown, the mechanism is also provided with electro-magnetic means for effecting the dis-

engagement thereof, said means comprising the magnetic member 34 carried by the latch 28, and the rigid armature 36 which is secured at one end thereof to the latch and to the movable contact arm. A spring 38 is interposed between the handle 24 and the movable arm 14, as illustrated.

The operation of the circuit breaker is described in detail in my above mentioned copending application. However, it will be understood that the bi-metallic element 28 operates to latch the manually operable actuator 22 to the movable contact member 14 and to unlatch said actuator from the movable contact member, the unlatching taking place upon deflection of the bi-metallic element 28 causing the disengagement of the free end 40 thereof from the bottom part 42 of the actuator 22 upon the occurrence of an overload, or under other abnormal predetermined current conditions in the circuit controlled by the circuit breaker. When the bi-metallic element 28 is deflected from engagement with the actuator 22, spring 38 is effective to move the contact member 14 to its open position, as illustrated in my copending application, wherein the contact 16 is disengaged from the companion stationary contact 18.

Pursuant to the present invention, and in order to provide for the fine or micromatic adjustments of the actuator for calibration purposes, the movable contact member 14 is provided with a generally circular, peripherally interrupted aperture 44. Said aperture is formed in the lower marginal edge of the narrower portion 46 thereof, on the free end of which the actuator 22 is pivotally mounted. It will be noted that the body portion 48 of the movable contact member 14 forms the wider and generally larger portion thereof and extends to the left (viewing Fig. 1) of the pivot pin 50 on which the movable contact arm is pivotally mounted.

The mechanism 11 is calibrated preferably prior to the insertion thereof in the housing portion 12. For calibration purposes, pursuant to my invention, it is necessary to provide only a sub-assembly 13 of the circuit breaker 10. Said sub-assembly includes the movable contact arm 14, the actuator 22 mounted at one end thereof, and the bi-metallic latch 28 which is secured at the bottom edge of the body portion 48 of the contact arm. In the uncalibrated condition of said sub-assembly 13, as illustrated in Fig. 2, the bottom or latching part 42 of the actuator may overlap substantially the full thickness of marginal edge 52 at the free end 40 of the bi-metallic latch. Then, with the movable arm 14 retained against movement, preferably in a suitable clamp or fixture (not shown), a tapered element or pin 54 is inserted into the aperture 44 and urged therein transversely of the movable member in any suitable manner. This will result in the displacement of the movable member 14 in its own plane. More specifically, the narrower portion 46 will bend upwardly, in the plane of movable arm 14, relative to the wider body portion 48 thereof. This will carry actuator 22 upwardly relative to latch 28 to decrease the extent by which the end part 42 of the actuator 22 overlaps the marginal edge portion 52 of the latch 28, for example, as illustrated in Fig. 3. Said figure corresponds to the Figure 5 in my copending application, the pin 54 corresponding to the pin 118 illustrated in said figure of said copending application. In this manner of practicing the invention, the pin remains in its adjusted position in the aperture, the opposing portions 56 and 58 at the inter-

rupted periphery thereof being moved away from each other by the displacement resulting from the insertion of said pin.

Pursuant to the presently preferred embodiment of my invention, illustrated in Figs. 5 and 6, the pin 54 is dispensed with and, in place thereof, I prefer to use a spindle or tool 60 provided with a tapered end 62. The sub-assembly 13, comprising the movable arm 14, the actuator 22 and the latch 28 is then retained as heretofore described. The spindle 60 is then inserted into the aperture 44 and urged therein by means of any suitable mechanism, until end portion 46 of the latch 28 has been displaced sufficiently upwardly in the plane of member 14 to provide the desired degree of overlap of the actuator end 42 on the latch edge 52 to obtain the desired calibration. This is clearly indicated in Fig. 5 wherein the uncalibrated sub-assembly is illustrated in broken line, said sub-assembly being in the same condition as illustrated in Fig. 2. The tapered end 62 of the spindle 60 is then pressed into the aperture until the portion 46 of the movable member 14 has been displaced in the plane thereof to the desired extent, as indicated in full line in Fig. 5, to illustrate the calibrated condition of the sub-assembly. The spindle 60 is then withdrawn from the sub-assembly which is now ready to be inserted into the housing part 12. Upon the proper placement of all the parts in the housing, the calibrated mechanism will be in the condition illustrated in Fig. 1. It will be apparent that further calibration is unnecessary since the sub-assembly has been calibrated prior to incorporation in the housing.

It will be noted that in the described methods of practicing my invention, the bi-metallic latch 28 is not moved during calibration since it is secured to body portion 48 of the movable member 14, which portion is not displaced. It is the actuator 22 which is moved relative to the latch since the actuator is carried by portion 46 which is displaced during calibration.

While I have shown and described the preferred embodiment of my invention, it will be understood that various changes may be made in the present invention without departing from the underlying idea or principles of the invention within the scope of the appended claims.

Having thus described my invention, what I claim and desire to secure by letters patent, is:

1. In an automatic circuit breaker, a movable contact member, said movable contact member having an actuator movably mounted on a part thereof and having a current-responsive device releasably engageable with said actuator for releasably latching said actuator to said member for movement of said member by said actuator, means for use in calibrating the circuit breaker comprising provision in said part of said member of means to facilitate displacement of said part in said member and thereby move said actuator in relation to said current-responsive device for adjusting the releasably engaged portions of said actuator and said current-responsive device.

2. In an automatic circuit breaker, a movable contact member, said movable contact member having an actuator movably mounted on a part thereof and having a current-responsive device releasably engageable with said actuator for releasably latching said actuator to said member for movement of said member by said actuator, means for use in calibrating the circuit breaker comprising provision in said part of said mem-

ber of means to facilitate displacement of said part in said member, said means comprising an opening at an edge portion of the member to receive a tool for causing said displacement of said part of the member and thereby move said actuator in relation to said current-responsive device for adjusting the releasably engaged portions of said actuator and said current-responsive device.

3. In an automatic circuit breaker, a movable contact member, an actuator movably mounted thereon, a thermally-responsive bi-metallic element carried by said member and having a free end in releasable engagement with said actuator to latch and unlatch said member thereto, said actuator and said element being provided on spaced portions of said member and means provided in said member to facilitate the relative displacement of said portions for moving said actuator relative to said free end whereby to calibrate said circuit breaker, said means comprising a marginal edge portion of said member in which there is defined a peripheral interruption.

4. In an automatic circuit breaker which comprises a movable contact member having an actuator movably mounted thereon and a thermally-responsive bi-metallic element carried by said member and having a free end in releasable engagement with said actuator to latch and unlatch said member thereto, means for use in calibrating the circuit breaker comprising provision in said member to facilitate the displacement thereof for moving said actuator relative to said free end whereby to calibrate said circuit breaker, said means comprising a marginal edge portion of said member in which there is defined a peripheral interruption, said edge portion being between the respective points of said member on which said actuator is mounted and said element is carried.

5. In an automatic circuit breaker, a movable contact member, an actuator movably mounted adjacent one end thereof, a thermally-responsive bi-metallic element carried adjacent the other end of said member and extending therefrom for releasable engagement with said actuator to latch and unlatch said member thereto, and means provided in said member to facilitate the displacement of said one end thereof relative to said other end thereof for moving said actuator relative to said element whereby to calibrate said circuit breaker, said means comprising a marginal edge portion of said member disposed between said ends thereof and provided with a peripheral interruption.

6. In an automatic circuit breaker, a movable contact member, an actuator movably mounted adjacent one end thereof, a thermally-responsive bi-metallic element carried adjacent the other end of said member and extending therefrom for releasable engagement with said actuator to latch and unlatch said member thereto, and means for calibrating said circuit breaker comprising a marginal edge portion of said member disposed between said ends thereof and provided with a peripheral interruption, and means in said peripheral interruption for moving said one end relative to said other end in the plane of said member for moving said actuator relative to said element.

7. A movable contact member for an automatic circuit breaker, said member having a marginal edge portion in which there is defined a peripherally interrupted aperture to facilitate the displacement of a portion of said member

in its own plane for calibrating the circuit breaker, and a tapered member in said aperture for effecting said displacement.

8. The method of calibrating a circuit breaker provided with a movable contact member having an actuator movably mounted on a part thereof and having a current-responsive device releasably engageable with said actuator for releasably latching said actuator to said member for movement of said member by said actuator, said method comprising displacing said part of the movable contact member relatively to another part thereof so as to move said actuator in relation to said current-responsive device for adjusting the releasably engaged portions of said actuator and said current-responsive device.

9. The method of calibrating a circuit breaker provided with a movable contact member having an actuator movably mounted on a part thereof and having a current-responsive device releasably engageable with said actuator for releasably latching said actuator to said member for movement of said member by said actuator, said method comprising providing an opening at an edge of said part of the movable contact member and pressing a tapered member into said opening transversely of the general plane of said part for displacing said part relative to another part of said movable contact member so as to move said actuator in relation to said current-responsive device for adjusting the releasably engaged portions of said actuator and said current-responsive device.

10. The method of calibrating a circuit breaker provided with a movable contact member having an actuator movably mounted on a part thereof and having a current-responsive device releasably engageable with said actuator for releasably latching said actuator to said member for movement of said member by said actuator, said method comprising providing an opening at an edge of said part of the movable contact member and pressing a tapered member into said opening transversely of the general plane of said part for displacing said part relative to another part of said movable contact member so as to move said actuator in relation to said current-responsive device for adjusting the releasably engaged portions of said actuator and said current-responsive device, and thereafter removing said member from said movable contact member.

11. The method of calibrating a circuit breaker provided with a movable contact member having an actuator movably mounted on a part thereof and having a current-responsive device releasably engageable with said actuator for releasably latching said actuator to said member for movement of said member by said actuator, said method comprising providing an opening at an edge of said part of the movable contact member and pressing a tapered member permanently into said opening transversely of the general plane of said part for displacing said part relative to another part of said movable contact member so as to move said actuator in relation to said current-responsive device for adjusting the releasably engaged portions of said actuator and said current-responsive device.

12. In an automatic circuit breaker having a movable contact member, actuating means mounted thereon, and a thermally-responsive bi-metallic element carried thereby for releasable engagement with said actuating means to latch and unlatch said member thereto, said actuating means overlapping said element in the engaged

condition thereof; the method of calibrating said circuit breaker comprising providing said movable member with a peripheral interruption intermediate said actuating means and said element and enlarging said interruption to displace a portion of movable member provided with said actuating means in the plane thereof for adjusting the extent of said overlap.

13. In an automatic circuit breaker having a planar movable contact member provided with a body portion and a narrowed extension, actuating means mounted on said extension, and a thermally-responsive bi-metallic element carried on said body portion and extending therefrom for releasable engagement with said actuating means to latch and unlatch said member thereto, said actuating means overlapping said element in the engaged condition thereof; the method of calibrating said circuit breaker comprising providing a peripherally interrupted aperture in a marginal edge portion of said member between said narrowed extension and said body portion, in-

serting a tapered element into said aperture and pressing said tapered element into said aperture for moving said narrowed extension in the plane of said movable member and relative to the body portion thereof for adjusting the extent of said overlap.

THOMAS M. COLE.
